(57) CLAIM

The ornamental design for eyewear, as shown and described.

DESCRIPTION

FIG. 1 is a perspective view of eyewear showing the new design;

FIG. 2 is a top view thereof;

FIG. 3 is a bottom view thereof;

FIG. 4 is a front elevation view thereof;

FIG. 5 is a rear elevation view thereof; and,

FIG. 6 is a right side elevation view thereof, the left side being a mirror image of the right side.

The broken lines showing surface ornamentation are for illustrative purposes only and form no part of the claimed design.

1 Claim, 4 Drawing Sheets
